(57) **CLAIM**

The ornamental design for an audio visual cart, as shown and described.

DESCRIPTION

FIG. 1 is a top perspective view of an audio visual cart showing our new design with an additional environmental display;

FIG. 2 is another top perspective view of the audio visual cart of FIG. 1 shown without the environmental display; FIG. 3 is a bottom perspective view of the audio visual cart shown in FIG. 2;

FIG. 4 is a front elevation view of the audio visual cart shown in FIG. 2;

FIG. 5 is a back elevation view of the audio visual cart shown in FIG. 2;

FIG. 6 is a left side elevation view of the audio visual cart shown in FIG. 2;

FIG. 7 is a right side elevation view of the audio visual cart shown in FIG. 2;

FIG. 8 is a top plan view of the audio visual cart shown in FIG. 2; and,

FIG. 9 is a bottom plan view of the audio visual cart shown in FIG. 2.

The broken lines in FIG. 1 showing the display depict unclaimed environmental subject matter only and form no part of the claim. All other broken lines in the drawings depict parts of the audio visual cart that form no part of the claim.

1 Claim, 9 Drawing Sheets
